UNITED STATES PATENT OFFICE.

MILTON L. DODGE, OF NEWBURYPORT, MASSACHUSETTS.

METHOD FOR ATTACHING MOLDED COUNTERS TO TURN SHOES.

Application filed March 7, 1922. Serial No. 541,667.

To all whom it may concern:

Be it known that I, MILTON L. DODGE, a citizen of the United States, residing at Newburyport, in the county of Essex and 5 State of Massachusetts, have invented new and useful Improvements in Methods for Attaching Molded Counters to Turn Shoes, of which the following is a specification.

This invention relates to a method and 10 certain features of the machine particularly intended for attaching counter stiffeners or counter stiffeners and shank pieces in position in the manufacture of turn shoes, and by which this operation may be rapidly and 15 accurately effected. Heretofore these parts have usually been attached while the last is in the unturned shoe, the shoe being supported in a nailing machine by a jack having in its top a pin for engagement in a 20 hole in the neck of the last. This jack is movable forwardly for the placing and removal of shoes and is then moved backwardly and raised up into cooperative relation to the nailing mechanism at each operation. 25

As is well known to those skilled in the art the position of the last pin hole varies greatly with different lasts and the lasts also vary considerably in height. In order 30 to take care of the variations in the position of the last pin holes laterally of the last, it has been proposed to mount the last pin in a block free to slide laterally of the jack so that the operator may move it laterally as it approaches the nailing mechanism 35 to correctly position it. The proper lateral positioning of this block, as well as vertical adjustments for varying heights of last requires considerable skill and care on the 40 part of the operator and slows production very considerably.

According to the present invention the last is removed before the counter is attached, and a block, fitting easily within the 45 heel portion of the shoe, is fixed rigidly to the top of the jack. The engagement of the upper at the heel end of the shoe about this block thus properly centers the shoe so that it is always presented in proper position laterally to the nailing mechanism, no adjustment being required for different shoes. 50

To further insure correct lateral positioning of the shoe relative to the nailing mechanisms, a centering guide may be employed 55 against which the shoe is moved beneath the nailing mechanism.

By this invention, therefore, the nailing of the counter in correct position is reduced to a mechanical operation in which the exercise of special skill or judgment is unnecessary, so that the operation is very materially speeded, the production of imperfect or inferior work eliminated, and a poorer quality of labor may be employed satisfactorily, thus materially cheapening the operation. 60 65

For a more complete understanding of this invention, reference may be had to the accompanying drawings in which

Figure 1 is a fragmentary side elevation 70 of the machine showing the relation of the shoe supporting jack to the nailing mechanism.

Figure 2 is a detail plan of the sole and counter gage. 75

Figure 3 is a side elevation of the shoe supporting block used when wood heel's are to be employed, other parts being shown in dotted lines.

Figure 4 is a top plan of a block used 80 where wood heels are to be employed.

Referring first to Figure 1, at 1 is indicated a jack post which is slideable forwardly and rearwardly in suitable guides on the vertical movable slide 2. This machine may be of any suitable type of nailing machine, as herein shown it being of the well known "Lightning" type. The jack 1 has at its outer end an upwardly extending post 3 which, in the ordinary use of the 90 machine for nailing heels, is used to support the toe of the shoe. At 4 is shown an adjustable heel post to the top of which is fixed a block 5. This block in the present invention is rigidly fixed to the top of the 95 post 4, centering pins 6 and 7 being shown to insure its correct positioning and a set screw 8 being employed to fasten the block rigidly in position. At 10 is shown a nailing block which is designed to receive nail's 100 in suitable perforations therein and to receive driving members for driving the nails into a shoe supported on the jack 1. This block 10 is preferably provided on its lateral sides with downwardly extending fingers 11 and on its rear face with a finger 12. These fingers may be of springy material, if desired, so that a molded counter, indicated by dotted lines at 13, may be pushed upwardly over the block 10, the fingers 11 and 12 passing outwardly thereof to retain it in position. 105

Where shank stiffeners are to be at-

tached also, these are assembled with the counters before the latter are positioned for attachment to the shoes. This nailing block, together with fingers, is fixed in position on the machine in a well known manner. The jack 1 may be moved outwardly, away from beneath the block 10, into the position shown in dotted lines, to facilitate the placing of the shoe thereon, this being done 5 when the slide 2 is depressed below cooperative relation with the nailing block. When the jack is in this position, an unturned shoe, the last having been removed, is placed over the block 5, the heel portion of the upper 10 extending down around the same, as indicated in dotted lines at 14. The toe rest 3 may support the toe portion of the shoe at this time but when the nailing of the counter is being effected it performs no function 15 in the present invention. The block 5 serves to center the shoe laterally, the upper 14 engaging about the sides thereof, so that the shoe sole is correctly related to the path of movement of the jack so that it will be 20 brought into proper cooperative relation with the block 10, and the counter thereon, without particular care on the part of the operator.

The jack is moved rearwardly beneath 25 the nailing block and the sole of the shoe engages between outwardly curved spaced arms 20 (see Figures 1 and 2) of a gage 21. This gage 21 is fixed to the upper end of a rod 22 which extends through a guide 30 flange 230 of a vertically extending track or guide member 23 against the forward face of which the gage slides. The rod 22 extends downward through an opening 24 of a bracket 25 which is fixed centrally to 35 a top cross member 26 of a yoke 27 made fast at opposite ends by turned flanges 28 to the top of the slide 2. Slight variations in the thickness of the sole are provided for by a spring 30 surrounding the 40 rod 22 and bearing in its lower end against the top face of the bracket 25 and at its upper end against a pin 31 extending transversely of the rod 22. This vertical movement is for the purpose of correctly positioning a counter-engaging gage or centering plate 35, which is also carried by the 45 rod 22 against the upper face of the gage 21. The gage 35 has a sloping inner face 36 which engages beneath the rear end of 50 the counter to properly position it relative to the sole in a lengthwise direction so that when the jack 1 is pushed rearwardly and the slide 2 raised upwardly, the parts are guided into proper relative position. The 55 nailing mechanism is then actuated to drive the nails in the block 10 through the sole-engaging flange of the counter in the usual manner to make it fast on the upper face of the shoe sole.

60 It is sometimes desirable to move the

gages 21 and 35 out of cooperative position with the jack and nailing block, as when shoes to which wood heels are to be applied, are being operated upon. For this purpose the guide member 23 is fixed to 65 the outer end of a screw 40 which is slideable through perforations in a pair of spaced jaws 41 upstanding from a bracket 42 which is made fast to a fixed part of the machine frame 43. Threaded on the screw 70 40 between the jaws 41 is a knurled nut 44, by turning which the guide member 23 may be moved forwardly or backwardly relative to the machine frame and into and out of cooperative relation with the jack and nailing block. In order to permit this motion without binding, the perforation 24 of the bracket 25 through which the rod 22 passes is formed flaring outwardly toward both 75 ends from an intermediate position to permit ready rocking of the rod 22 with reference to the bracket. The position of these parts when the gages are out of operative 80 position is shown in dotted lines in Figure 3 in which also a modified construction of jack 85 block particularly intended for use with wood heels is shown at 50.

As is well known the outer edge of the heel portion of the shoe to which a wood heel is to be attached is beveled off, and before the shoe is turned the upper is unattached to the heel portion of the sole. When a wood heel is to be affixed therefore, the block 50 has a marginal upwardly extending flange portion 51, as shown in Figures 3 and 4, within which the sole extends and against the top of which the edge of the counter may rest. The block 50 may be of a width sufficient to substantially fit the width of the sole if desired, as shown in 90 full lines in Figure 4, but in order that a single block may serve for several sizes of shoe and therefore require infrequent change of blocks for different sizes, they may be made somewhat narrower than the 95 shoe to be operated upon as indicated in dotted lines at 52 (see Figure 4). When such a narrow block is employed it is an easy matter for the operator to center the sole laterally on the block by placing his 100 fingers beneath the edge of the sole and in contact with the edge of the block, the upper, as before stated, being unattached at this point to the sole and offering no obstruction to this action. The sole and counter gages are not used at this time, and in 105 order to position the jack correctly rearwardly beneath the nailing block with these gages out of position, an adjustable stop 110 herein shown as comprising a cap screw 55 is threaded in a boss 56 projecting inwardly from the yoke member 26. This cap screw may be adjusted and then fixed 115 in position by a lock nut 57 thereon so that when the jack 1 is pushed inwardly to im- 120 125 130

- pinge on the head thereof, it is correctly positioned for vertical movement into operative relation to the nailing block. While as before stated the last is removed prior to the attachment of the counter and before the shoe is turned, it is usually preferable to turn the toe portion of the shoe before the counter is attached, this being shown in dotted lines in Figures 1 and 3. When this is done the toe portion may be supported, when the shoe is initially placed on the jack, by means of the toe rest 3, and when the jack is moved upwardly and the sole is engaged between the heel block and the nailing block, the fore part of the shoe is raised upwardly off the toe rest by the engagement of sole and counter between the blocks 5 and 10 substantially as shown. If the forepart of the shoe is not turned prior to the attaching of the counter, the toe rest is likely to interfere with the downwardly extending upper of the shoe.

Having thus described certain embodiments of this invention it should be evident to those skilled in the art that many modifications and changes might be made therein without departing from its spirit or scope as defined by the appended claims.

I claim:

- 30 1. That improvement in the art of fastening counters to turn shoes which comprises removing the last before the shoe is turned, placing the unturned heel portion of the shoe in inverted position over a block movable in a determined path into cooperative relation to a nailing mechanism, placing a molded counter in position on the nailing mechanism, moving the block with the shoe thereon to said nailing mechanism, and nailing the counter to the shoe sole.
- 35 2. That improvement in the art of fastening counters to turn shoes, which comprises removing the last from the unturned shoe, placing the shoe sole up over a heel block of a backwardly, forwardly and vertically movable jack while the block is down and moved forwardly, fixing a counter in an upright position on a nailing mechanism positioned vertically over the backward position of said block, moving said block and shoe backwardly, raising said jack into cooperative relation to said nailing mechanism, and then nailing the counter in position on the upwardly presented surface of the shoe sole.
- 40 3. That improvement in the art of fastening counters to turn shoes, which comprises removing the last from the unturned shoe, placing the shoe sole up over a heel block
- 45 4. The improvement in the art of fastening counters to turn shoes which comprises removing the last from the unturned shoe, placing the shoe sole up over a heel block, placing a molded counter on a nailing block, relatively moving said heel and counter blocks to bring the counter into proper relation to the upwardly presented side of the shoe sole, and nailing the counter in position.
- 50 5. That improvement in the art of attaching molded counters to turn shoes which comprises removing the last from the unturned shoe, placing the shoe over a heel block, and placing and attaching a counter on the exposed heel end face of the shoe sole.
- 55 6. That improvement in the art of fastening counters and shank pieces to turn shoes which comprises removing the last from the unturned shoe, placing the shoe over a heel block, and placing and attaching a previously assembled shank piece and counter on the exposed face of the shoe sole.
- 60 7. That improvement in the art of attaching molded counters to turn shoes which comprises removing the last from the unturned shoe, and attaching the counter on the exposed heel end face of the shoe while supporting the shoe at the opposite face of the sole.
- 65 8. That improvement in the art of attaching molded counters to turn shoes which comprises removing the last from the unturned shoe, turning the forepart of the shoe, and attaching the counter on the exposed heel end face of the shoe while supporting the shoe at the opposite face of the sole.

In testimony whereof I have affixed my signature.

MILTON L. DODGE.
